CRANE CONTROL

Remi Bollaert, Oakland, Calif., assignor to Westinghouse Electric Corporation, East Pittsburgh, Pa., a corporation of Pennsylvania

Application September 12, 1946, Serial No. 696,568

10 Claims. (Cl. 254—173)

1

My invention relates to electric hoist control systems, preferably for bridge type cranes.

It has been proposed to suspend two hook assemblies from a single cable and to operate them selectively by having the motor-driven cable drum act on only one of the hook assemblies while the other is held idle in its top limit position. As a rule, one of the hook assemblies, serving for heavy duty operation, is heavy in weight as compared with the other and is locked in its top position whenever the light hook assembly is to operate, while the light hook bears against a stop under the cable pull exerted by the heavier hook when the latter is in operation.

It is an object of my invention to provide an electric control system which is capable of operating the two hook assemblies of hoists and cranes of the just-mentioned type with an optimum degree of safety and reliability of selective operation and which secures an automatic protection from faulty manipulations with the aid of simple electric devices and circuit connections.

In one of its more specific aspects, the invention aims at devising a selective control system which limits the hoist motor to slow-speed low-torque operation when either hook assembly is close to the uppermost abutment or latching position, thus preventing overstressing and damaging the stop and latching means and the appertaining electric switches, so that no exceptional skill or attention is required from the operator of such a hoist.

Another one of the more specific objects of the invention, in conjunction with the foregoing, is to devise a control system which inherently prevents abusing the stop or latch means of the hook assemblies by suspending unduly heavy loads from the hooks while the latter are held in their topmost limit position in which they are supposed to carry no appreciable hoisting load.

It is further an object of the invention to provide an electric control system of simple design which requires a relatively low number of trolley wires, as compared with the customary single-hook crane trolleys, so that the system according to the invention can readily be installed in existing single hook trolleys in order to convert them for double-hook operation.

These and other objects, as well as the means provided by my invention for achieving them, will be apparent from the following description of the embodiment exemplified by the drawing, in which:

2

Figure 1 shows the circuit diagram and scheme of the appertaining hoisting assemblies, while

Fig. 2 represents schematically a double-hook trolley of a bridge type crane to be controlled by the system of Fig. 1.

Referring at first to Fig. 2, numeral 1 denotes the trolley whose wheels 2 rest on the rails 3 of a crane bridge. The propulsion motor and control equipment of the trolley is not relevant to the present invention and hence not indicated in Fig. 2. Mounted on the trolley is a drum 4 for a hoist cable 5 from which two hook assemblies, a heavy main assembly MH and a light-weight auxiliary assembly AH are suspended (Fig. 1 and 15). The cable 5 passes from the drum in several turns around a pulley journaled about the shaft 6 of a block 7 which carries the main hook 8 and a latch and switch control member 9. Thence the cable is led over an idler sheave 10 and passes over a pulley 11 in the block 12 of the auxiliary assembly. Block 12 carries the auxiliary hook 13 and is designed to abut against a stop structure 14 (Fig. 1) of the trolley frame when the assembly is in its illustrated top limit position. 20 The end of cable 5 is secured to the trolley frame. This illustrated way of roping provides equal lifting speeds for the two hooks at any given reeling speed of the cable, but can be replaced by a roping and pulley arrangement for other desired speed ratios. For instance, by omitting the pulley 11 and attaching the cable end to the block 12, the auxiliary assembly AH can be given twice the speed and half the lift of the main hook; or by adding a stationarily journaled 25 sheave and second pulley to the main assembly, twice the speed and one-quarter the lift of the main hook can be given to the auxiliary assembly. Hence, the illustrated roping should be understood to represent merely one of the designs applicable in conjunction with the invention. The main hook assembly MH is considerably heavier than the auxiliary assembly so that the latter is always pulled up against the stop 14 when the main hook is in operation. 30 The main hook assembly MH is connected through a reduction gear 15 (Fig. 2) with the hoist motor M, which in the embodiment of Fig. 1 is shown as consisting of a wound-rotor motor with three primary terminals T1, T2, T3. The transmission between motor M and drum 4 includes a spring-set, friction brake B (Fig. 1) whose magnet coil 16 must be energized in order to release the drum. Coil 16 is connected across motor terminals T1 and T3 so that the brake B is set 35 when the motor is deenergized and automatically 40 45 50 55

released when power is applied to the motor. The secondary or rotor circuit of motor M includes two sets of resistors denoted by 17 and 18 in Fig. 1.

A latching device 19, mounted on the trolley, has a spring-biased latch 20 (Fig. 1) to engage a latch opening of member 9. An electromagnetic device, such as a torque motor or thruster T serves to withdraw the latch in order to release the main assembly for operation. Mounted on the trolley are further four limit switches S1, S2, S3, S4 (Figs. 1 and 2). Switches S1 and S2 are actuated by the member 9 of the main assembly and switches S3 and S4 cooperate with the auxiliary assembly in the manner described in a later place.

It is assumed that, as customary, the hoist motor is controlled from a cab that is mounted on the crane bridge separate from the trolley. The necessary connections between cab and trolley are formed by trolley wires and appertaining slide or roller contacts. Only the trolley wires appertaining to motor M are shown in Fig. 1. They comprise three power supply wires 21, 22 and 23 whose appertaining slide contacts are connected to motor terminals T1, T2 and T3 respectively. Three power wires 24, 25, 26 connect the secondary terminals of motor M with the resistors 17 and 18 and with the master controller MC in the cab; and six further trolley wires, denoted by 36 through 35, connect the limit switches and the thruster T with the control equipment of the cab.

The master controller, though here shown as a drum controller, may consist of any suitable type of control apparatus. As illustrated, the controller has a group of contact fingers, such as those denoted by 36, to cooperate with a number of contact segments such as those denoted by 37, 38 and 39. The exemplified controller, shown in developed form, has an "off" position, three hoisting positions, and three lowering positions.

Associated with the circuits controlled by the master controller are four push button contacts BR, BS, BM and BA. Button BR must be depressed to start the system or to reset it for renewed operation after each tripping of the main contactor LV mentioned below. Button BS, when depressed, trips the main contactor and stops the motor; and buttons BM and BA serve to select the main hook or the auxiliary hook for operation. The four buttons are installed within easy reach of the operator, with buttons BM and BA preferably located in the handle of the master controller MC so that they can be depressed while the motor controller is being actuated.

The main contactor LV, as here shown, is designed as a low voltage protective relay of the type customarily used on cranes. It may be equipped for overload protection unless separate overload protection is desired. Another contactor, denoted by RH, serves as a hoisting relay and closes only when one of buttons BM and BA is depressed.

A relay RT controls the thruster T. The system includes further the relays marked RL, R2, R4, RM and RA. Relay RL responds to the closing of limit switch S1 or S3. Relays R2 and R4 are controlled by the limit switches S2 and S4 respectively, while relays RM and RA operate under control by the respective selector buttons BM and BA.

Details of design and performance of the above-mentioned system elements will be re-

ferred to presently in conjunction with a description of the operation of the control system.

With assemblies MH and AH in the illustrated uppermost positions, limit switches S1 and S3 are open and limit switches S2 and S4 are closed. When the master controller MC is in the "off" position, as shown, the energization of the power supply busses L1, L2, L3, by the closing of a main switch (not illustrated), does not as yet cause any operation of the hoist motor but has immediately the effect of adjusting the system as follows:

Relay RL picks up in circuit:

L1—57—BA—BM—39—L3 (1)

and opens its contact 56.

Relay R2 picks up in circuit:

L1—60—71—34—T2—S2—73—30—L3 (2)

and opens contact 58 while closing contact 59.

Relay R4 picks up in circuit:

L1—63—74—35—34—72—30—L3 (3)

and opens its contact 62 while closing contact 61. Due to the opening of contacts 58 in relay R2 and 62 in relay R4, coil 55 of the hoist relay RH is disconnected, and relay RH remains dropped out. Relays RA, RM and RT remain also deenergized.

After energizing the buses L1, L2, L3, the operator depresses temporarily the button BR. This has the effect of closing the coil circuit of the low voltage contactor LV:

L1—38—BR—BS—45—39—L3 (4)

Contactor LV picks up and closes the main contacts 41, 42, 43 while also closing a self-holding circuit at back contact 44. Hence, contactor LV remains picked up as long as no voltage failure occurs unless it is tripped by the actuation of the stop contact BS. If, after dropping out of contactor LV, the master controller is not in its "off" position, the circuit of coil 45 in contact LV remains interrupted until the segment 39 is placed in the illustrated position by returning the motor controller to the "off" position. With both hooks in top position, the motor controls, of course, cannot be set for hoisting operation. If the master controller is nevertheless turned for hoisting, the holding circuit of coil 45 is interrupted at segment 39 so that contactor LV is tripped. Hence, with mains L1, L2, L3 energized and after temporarily depressing the start button BR, the system permits at first only lowering operations until the hook to be used has descended from the illustrated position.

If the main hook is to be used, the operator first depresses the main button BM momentarily. Due to the actuation of button BM, the circuit of coil 57 is opened so that relay RL closes its contact 58 and thereby completes for coil 50 of the main hook relay RM the circuit:

L3—50—BM—55—38—L1 (5)

Relay RM, by closing its contact 48, energizes the coil 61 of relay RT in circuit:

L3—61—59—61—48—L1 (6)

Relay RT closes the self-sealing circuit

L3—67—59—66—L1 (7)

and hence stays picked up when shortly thereafter push button BM is released and interrupts the coil circuit of relay RM and causes the latter to drop out. As a result, relay RT remains picked up and, by closing its contacts 64 and 65, closes the circuit of thrust or motor T through trolley

wires 32 and 33. Hence, latch 20 is withdrawn and hook MH is ready to be lowered. Then the master controller is turned in the lowering direction. In the first position for lowering, the master controller connects bus L1 through contact 41 with trolley wire 21 and primary terminal T1 of motor M, and bus L3 through contact 43 and trolley wire 23 with motor terminal T3, while bus L2 is in connection with terminal T2 through contact 42. Thus the motor M is energized to run the cable drum 4 in the lowering direction with all secondary resistors 17 and 18 effective for minimum acceleration. Simultaneously, the brake coil 16 is energized and releases the brake B. Hook MH is lowered at slow speed so that first the limit switch S2 is opened and then the limit switch S1 closed as the member 8 leaves the location of the limit switch assembly.

The opening of limit switch S2 interrupts the circuit of coil 60 in relay R2. This relay drops out and, at contact 59, opens the self-sealing circuit of relay RT which in turn deenergizes the thruster T and resets the latch 20 for catching and holding performance.

The closing of limit switch S1 interconnects conductors 73 and 76 and thereby the trolley wires 30 and 31 thus placing the conductor 75 in connection with bus L3. This establishes for coil 57 of relay RL the parallel circuit:

L1—57—75—31—76—S1—73—30—L3 (8)

so that relay RL will stay picked up independently of the future condition of the push buttons BM or BA during the continuance of the lowering performance and thereby prevents energization of RM or RA.

The condition of the system thus reached remains unchanged when the motor controller is further advanced to the second and third lowering positions except that in the second position the resistors 17 of the secondary motor circuit are shorted while in the third position all resistors 17 and 18 are shorted for corresponding increases in lowering speed.

When the main hook MH is in lowered position, i. e., with limit switch S1 closed and limit switch S2 open, the actuation of the master controller in the hoisting direction initiates the following performance.

In the "off" position of the master controller, relay RL is picked up and maintains its contact 56 open due to the closing of limit switch S1, and relay R2 remains dropped off due to the opening of switch S2. Since relay R4 is energized through the limit switch S4 of hook AH, coil 55 of relay RH is deenergized so that contacts 51 and 53 remain open during hoisting of the main hook.

In the first position hoist of controller MC, the voltage contactor LV remains now energized in circuit;

L1—44—BS—45—BM—BA—75—
31—76—S1—73—30—L3 (9)

The master controller now connects bus L1 through contact 41 with trolley wire 23 and motor terminal T3, while bus L3 is connected through contact 43 and controller MC with trolley wire 21 and motor terminal T1. The connection of terminal T2 to bus L2 remains as before. Hence the motor is now energized to run reversed with all secondary resistors 17, 18 in. In the second position hoist, resistors 17 are shorted by the master controller, and in the third hoisting position all secondary resistors 17, 18 are shorted for increased hoisting speed.

During operation of the main hook, the auxiliary hook is held in top limit position under the pull exerted by the overbalanced main hook and hook load. If, after using the main hook, it is desired to operate with the auxiliary hook, the main hook must first be lifted into its top limit position. When the raising hook trips the limit switch S1, this switch opens the circuit (8) of coil 57 in relay RL so that contact 56 closes, and it also interrupts the coil circuit (9) of contactor LV, thus disconnecting the power supply at contacts 41, 42, 43. Consequently, when the main hook reaches the limit switch S1, the drive is automatically stopped. The operator now indicates his intention to use the auxiliary hook by depressing the button BA. This causes the motor M to continue pulling up the main hook at slowest speed until the hook is caught by latch 20 and closes the limit switch S2. It is required, however, that the master controller be placed in "off" position and the contactor LV closed by actuation of button BR in order to permit this pulling-up operation. The circuit then completed at button BA includes coil 47 of relay RA and extends as follows:

L1—38—56—BA—47—L3 (10)

Relay RA picks up and, by closing its contact 46, energizes the coil 55 of the hoist relay RH in circuit:

L1—46—58—55—L3 (11)

Relay RH closes the power supply circuit at contacts 51 and 53 and thus causes the motor M to run in the hoisting direction with all resistors 17, 18 inserted in the secondary motor circuit.

As soon as the main hook is locked by latch 20 and limit switch S2 closed, the circuit (2) of coil 60 in relay R2 is closed so that the coil circuit (11) of relay RH is opened at contact 58, thus interrupting the power supply at contacts 51 and 53 and again stopping the motor.

Then, when the operator turns the master controller in the lowering direction, the motor M will run accordingly. However, since now the relays RM and RT are deenergized, the thruster T remains idle and the main hook latched. As a result, the auxiliary hook is now lowered.

During its initial downward travel, hook assembly AH opens first the limit switch S4 and then closes the limit switch S3. Switch S4 breaks the coil circuit (3) of relay R4 so that contact 62 closes in preparation of a still open circuit for coil 55 of the hoisting relay RH. Switch S3, by closing, energizes coil 57 of relay RL in circuit:

L1—57—75—31—76—S3—73—30—L3 (12)

so that the contact 56 opens. During lowering of the auxiliary hook, the master controller in first, second, and third positions lowering controls the primary and secondary motor circuits in the same manner as described above with reference to main hook operation. The hoisting performance in the three hoist positions of the master controller is likewise substantially as described above except that, due to the latching of the main hook, the auxiliary hook is now in use.

When the auxiliary hook is lowered from its top limit position and it is desired to use the main hook, the operator first hoists the auxiliary hook until it trips the limit switch S3. This opens the coil circuit (12) of relay RL whose

contact 56 closes, and interrupts also the holding circuit:

L1—44—BS—45—BM—BA—75—
31—76—S3—78—38—L3 (13)

of the contactor LV. The power supply is cut off at contacts 41, 42, 43 of contactor LV, and the motor stops. The operator then resets the system by turning the master controller into "off" position and depressing the reset button BR. He then signals his intention to use the main hook by actuating the button BM. This energizes the coil 59 of relay RM in circuit.

L3—50—BM—56—38—L1 (14)

Contact 49 of relay RM closes for the hoist relay RH the coil circuit:

L1—49—32—55—L3 (15)

so that the motor M is energized through contacts 51 and 53 of relay RH for hoisting at lowest speed with all resistors of the secondary motor circuit inserted. Thus, the auxiliary hook inches upward until it closes the limit switch S4. Now, relay R4 picks up in circuit:

L3—38—73—S4—35—74—63—L1 (16)

main hook to auxiliary hook operation thus pre-RH, thus stopping the motor by interrupting the power supply at contacts 51 and 53. The closing contact 61 of relay R4, with button BM depressed and relay RM picked up, completes the coil circuit (6) for relay RT which continues holding itself by virtue of its self-sealing circuit (7) and causes the thruster T to withdraw the latch 20. The latch is held out until the operator moves the master controller on first point lowering. Then, the limit switch S2 disconnects relay R2 so that contact 59 opens the self-sealing circuit (7) and causes relay RT to cut off the thruster. Thereafter, limit switch S1 is opened and the further performance is as described in the foregoing.

The essential characteristics and advantages of the control system will now be recognized with reference to the above-described embodiment.

The system enforces automatically a slow and safe operating speed during the transition from main hook to auxiliary hook operation thus preventing overstress and damaging of the limit switches, latching means, stops, cable and pertaining equipment. This is achieved by the fact that the hoist motor cannot be operated at other than minimum speed once the operating hook moves in the uppermost part of travel between the two limit switches. Once the raising hook has reached the limit switch S1 or S3, the master controller can no longer be used to run the motor at higher speeds. As a matter of fact, in the illustrated embodiment the master controller is then always "off" and the motor is controlled only by button BM or BA and limited to minimum operating speed. On the other hand, the system prevents using the button control for causing the hoist to creep at minimum hoisting speed for an undue length of time. This prevention of improper operation is achieved by the fact that the push button control circuits receive excitation through relay RL only after the hook has reached the limit switch S1 or S3. In other words, nothing will happen to affect the crane performance if the main or auxiliary control buttons BM, BA are pushed while the hook assemblies are not sufficiently close to their

top limit positions. Should the operator hoist a load up to the top limit and then try to hold it with the latch on the main hook, or should he try to leave a load suspended on the auxiliary hook close to the top limit position, such an operation becomes impossible if the load has an appreciable weight. This will be recognized from the fact that the motor can be operated only with all secondary resistors in circuit as soon as the

limit switch S1 or S3 is reached. Consequently the available hoisting torque is too low for lifting substantial loads above these limit switches and, hence, to hold such loads latched or suspended in the uppermost positions.

15 The system is further distinguished by its economy of equipment necessary for controlling the two hook assemblies. Only four more trolley wires are required in comparison with the conventional systems with only one hook assembly. 20 This facilitates installing a system according to the invention on existing bridge type cranes with a control cab mounted on the bridge.

As mentioned, the light auxiliary hook assembly can be designed to operate at a speed different from that of the main hook assembly without requiring any change in the electrical equipment according to the present invention.

It will be obvious to those skilled in the art that systems embodying my invention can be altered and modified with respect to details of circuit elements and circuit connections without departing from the objects and principles of the invention and within the scope of its essential features set forth in the claims annexed hereto.

25 I claim as my invention:

1. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, limit switch means disposed to be actuated by said main assembly when the latter is in said top position, limit switch means disposed to be actuated by said auxiliary assembly when the latter is in top limit position, operator-actuable master control means connected to said motor for controlling its speed torque performance in hoisting and lowering direction, operator-actuable contact means for selecting of said assemblies for operation by said motor, and relay means connecting said selector contacts and said master controller with said limit switch means and said latch releasing device so as to permit releasing said latch means, for subsequent lowering of said main assembly from said top position, only when said auxiliary assembly is in its top position and said master control means in "off" condition and to permit selecting said auxiliary assembly, for subsequently lowering it from its top position, only when said main assembly is latched and said master control means is in "off" condition.

2. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lower-

ing said main assembly from said position, a first limit switch means disposed near the top position of said main assembly and having a lower limit switch and an upper limit switch, a second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting of said assemblies for operation by said motor, relay means connected with said master control means and said lower limit switches for limiting said motor to low speed operation when the selected assembly is raised up to the appertaining lower limit switch and relay means connected with said upper limit switches for stopping said motor when the raising assembly reaches the appertaining upper limit switch.

3. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting of said assemblies for operation of said motor, relay means connected with said master control means and said lower limit switches for limiting said motor to low speed operation when the selected assembly is raised up to the appertaining lower limit switch, relay means connected with said upper limit switches for stopping said motor when the raising assembly reaches the appertaining upper limit switch, and a relay controlled by said second limit switch means and connected with said contact means so as to permit selecting said main assembly for operation and causing said device to release said latching means only when said auxiliary assembly is in its top position.

4. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque con-

ditions, operator-actuable contact means for selecting of said assemblies for operation of said motor, relay means connected with said master control means and said lower limit switches for limiting said motor to low speed operation when the selected assembly is raised up to the appertaining lower limit switch, relay means connected with said upper limit switches for stopping said motor when the raising assembly reaches the appertaining upper limit switch, and a relay controlled by said upper limit switch of said first limit switch means and connected with said contact means so as to permit selecting said auxiliary assembly for operation only when said main assembly is latched in its top position.

5. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting one of said assemblies for operation by said motor, relay means connected with said master control means and said lower limit switches for limiting said motor to low speed operation when the selected assembly is raised up to the appertaining lower limit switch, relay means connected with said upper limit switches for stopping said motor when the raising assembly reaches the appertaining upper limit switch, and a relay controlled by said upper limit switch of said first limit switch means and connected with said contact means so as to render said contact means operative, for selecting one of said assemblies for operation, only when both assemblies are in their respective top position.

6. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting of said assemblies for operation by said motor, relay means connected with said master control means, and said lower limit switches for limiting said motor to low speed operation when the selected assembly is raised up to the appertaining lower limit switch, relay means connected with said upper limit

switches for stopping said motor when the raising assembly reaches the appertaining upper limit switch, a relay controlled by said upper limit switches and connected with said contact means so as to render said contact means operative, for selecting one of said assemblies for operation, only when both assemblies are in their respective top position, and a latch release relay disposed for controlling said device and connected with said second limit switch means, said selector contact means and said master control means so as to release said latching means upon selected actuation of said contact means only when said motor control means are in "off" condition.

7. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting one of said assemblies for operation by said motor, relay means connected with said master control means and said lower limit switches for stopping said motor when one of said assemblies is raised up to the appertaining lower limit switch, a hoist relay controlled by said contact means and said limit switch means so as to energize said motor for slow-speed hoisting when said latter lower limit switch is actuated by said latter assembly and when thereafter said contact means are actuated by the operator to select said other assembly for subsequent operation, and relay means connected with said upper limit switches for stopping said motor when the raising assembly reaches the appertaining upper limit switch.

8. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting one of said assemblies for operation by said motor, relay means connected with said master control means and said lower limit switches for stopping said motor when one of said assemblies is raised up to the appertaining lower limit switch, a hoist relay having a coil

circuit controlled by said contact means and said limit switch means so as to energize said motor for slow-speed hoisting when said latter lower limit switch is actuated by said latter assembly and when thereafter said contact means are actuated by the operator to select said other assembly for subsequent operation, and further relay means connected with said upper limit switches for stopping said motor when the raising assembly reaches the appertaining upper limit switch.

9. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting one of said assemblies for operation by said motor, relay means connected with said master control means and said lower limit switches for limiting said motor to low speed operation when the selected assembly is raised up to the appertaining lower limit switch, relay means connected with said upper limit switches for stopping said motor when the raising assembly reaches the appertaining upper limit switch, a release relay connected to said device and having a coil circuit controlled by said contact means and said first limit switch means so as to cause said device to release said latching means when said contact means are actuated for selection of said main assembly while said main assembly is in its top position, said coil circuit having a self-holding branch in interlock association with said lower switch of said first limit switch means so that said release relay and said device remain energized upon actuation of said contact means as long as said main assembly is above said latter switch and are deenergized when said main assembly is below said latter switch.

10. A control system for a hoist having a heavy main hook assembly, a light auxiliary hook assembly and a single cable from which said assemblies are suspended, and comprising in combination a hoist motor for operating said cable to selectively hoist and lower one of said assemblies, means for latching said main assembly in its top limit position, an electric device for releasing said latching means to permit lowering said main assembly from said position, first limit switch means disposed near the top position of said main assembly and having a lower limit switch and an upper limit switch, second limit switch means disposed near the top position of said auxiliary assembly and having a lower limit switch and an upper limit switch, operator actuatable master control means connected to said motor for controlling it to run in hoisting and lowering directions under selective speed torque conditions, operator-actuable contact means for selecting one of said assemblies for operation by said motor, a relay controlled by said upper limit

switches and connected with said contact means and being motor controlled so as to render said contact means operative for selection of one of said assemblies only when both assemblies are in their operative top position and said master control means are in "off" condition, a latch release relay disposed for controlling said device and connected with said second limit switch means, said selector contact means and said master control means so as to release said latching means upon selected actuation of said contact means only when said master control means are in "off" condition, a hoist relay having a coil circuit controlled by said contact means and said limit switch means so as to energize said motor for slow speed hoisting when said latter lower limit switch is actuated by said latter assembly and when thereafter said contact means are actuated by the operator to select said other assembly for subsequent operation, said relay means having interlock contacts disposed in said coil circuit to pre-

10

vent said hoist relay from energizing said motor when one of said assemblies is lowered below said appertaining lower limit switch, relay means connected with said upper limit switches for stopping said motor when the raising assembly reaches the appertaining upper limit switch.

REMI BOLLAERT.
